(57) **CLAIM**

The ornamental design for a display screen portion with graphical user interface for adding profile picture, as shown and described.

DESCRIPTION

The FIGURE is a front view of a display screen portion with graphical user interface for adding profile picture showing our new design.

The broken line showing of a display screen portion with graphical user interface is included for the purpose of illustrating portions of the article and forms no part of the claimed design.

1 Claim, 1 Drawing Sheet
